UNITED STATES PATENT OFFICE.

FREDERIC LATULIP, OF SYRACUSE, NEW YORK, ASSIGNOR OF ONE-HALF
TO EMIL LAASS, OF SAME PLACE.

CHAIR-SEAT AND CHAIR.

SPECIFICATION forming part of Letters Patent No. 317,382, dated May 5, 1885.

Application filed January 24, 1884. (No model.)

To all whom it may concern:

Be it known that I, FREDERIC LATULIP, of Syracuse, in the county of Onondaga, in the State of New York, have invented new and useful Improvements in Chair Seats and Backs, of which the following, taken in connection with the accompanying drawings, is a full, clear, and exact description.

This invention has for its objects to provide an improved seat or back for chairs, settees, and other like articles, which will be strong and durable and ornamental, and which can be supplied to the trade at reasonable cost in such form as to be conveniently secured to an article of furniture, as more fully hereinafter described.

Heretofore chair and settee seats and backs have been constructed of plain sheets of vulcanized caoutchouc or rubber, or of such sheets punched or perforated mechanically after vulcanization, and also of paper or pasteboard peculiarly treated and embossed to give it an ornamental configuration. The articles as thus constructed do not possess the requisite qualities of a chair seat or back, as, unless made very heavy or of very heavy material, they soon wear out or give way, and this is especially the case in the perforated caoutchouc or rubber seats and backs, the perforations, while serving to lighten the articles, materially weakening the same and rendering them extremely liable to break down.

My invention further has for its object to economize material without detracting from the strength of the article, as more fully hereinafter specified. By my invention these objections are wholly obviated, and a light, strong, durable, and ornamental article is produced.

In the drawings, Figure 1 is a plan view of a chair-seat constructed according to my invention. Fig. 2 represents a similar view of a modification of the same. Fig. 3 is a transverse section taken on the line $x x$ of Fig. 2; and Fig. 4 is a view, partly in elevation and

partly in section, showing the press and the means of forming my improved article.

In carrying out my invention the caoutchouc, rubber, or gutta-percha in a raw state, with a suitable admixture of sulphur or other vulcanizing material in proper quantity and suitable shape, is placed between the parts A, B of a mold, as shown in Fig. 4, and compressed between the same by means of a screw, C, or in any other convenient manner. The caoutchouc, rubber, or gutta-percha in this state is soft and plastic, and is readily forced into and takes the configuration of the faces of the mold. The said faces are formed with indented grooves D, crossing or intersecting each other, and forming corresponding ribs, E, in the molded material. Where extreme lightness and provision for ventilation is desired in the finished article, the faces of the molds between the intersecting grooves are formed with projections, which leave openings F between the intersecting ribs of the article, as indicated in Fig. 2 of the drawings. When thus formed, the material, which would otherwise fill the spaces between the intersecting ribs, is forced or crowded up to form such ribs, thus saving the material and effecting an important advantage by lessening in cost without impairing the strength of the article. The article is then subjected to the usual vulcanizing temperature while in the molds, by means of which it becomes hardened, losing its plasticity, but preserving its shape. As thus constructed the articles possess material advantages over other articles of this class, for the reason that, being formed under powerful compression, the parts are compacted, and possess the greatest possible strength, the intersecting ribs re-enforcing and adding to the strength, while the openings, which render the article extremely light, do not detract from its strength, as in the case of punched or cut apertures.

Having thus described my invention, what

I claim, and desire to secure by Letters Patent,
is—

5 A seat or back for chairs or other articles
of furniture, composed of caoutchouc, rubber,
or gutta-percha, made with a series of inter-
secting re-enforcing ribs, and with a plain
rim for securing the seat or back to the frame,
substantially as and for the purpose specified.

10 In testimony whereof I have hereunto signed
my name and affixed my seal, in the presence of

attesting witnesses, at Syracuse, in the county
of Onondaga, in the State of New York, this
11th day of January, 1884.

FREDERIC ^{his} LATULIP. [L. S.]
mark.
